UNITED STATES PATENT OFFICE.

DANIEL J. DIEL, OF JERSEY CITY, NEW JERSEY.

HOLE-CLOSURE.

1,089,335.

Specification of Letters Patent.

Patented Mar. 3, 1914.

Application filed March 29, 1913. Serial No. 757,553.

To all whom it may concern:

Be it known that I, DANIEL J. DIEL, a citizen of the United States, and a resident of Jersey City, in the county of Hudson and State of New Jersey, have invented a new and Improved Hole-Closure, of which the following is a full, clear, and exact description.

This invention relates to metal or other fireproof constructions, and has particular reference to devices for temporarily or permanently closing certain holes or openings in fireproof constructions as, for instance, the holes or openings for the installation of electric conduits or the like. This specific reference to the use of the device, however, is to be understood as being illustrative rather than a limitation, for the device is applicable in many different ways and for different specific purposes.

Among the objects particularly aimed at is to provide a cheap reliable metal closure which may be quickly secured in place, substantially closing the hole or opening, but which may be removed with facility by a suitable simple tool, when necessary, for reopening the hole.

A further object of the device is to simplify the closure, providing the least possible number of reliable parts, and practically removing the possibility of any part becoming lost or misplaced.

The foregoing and other objects of the invention will hereinafter be more fully described and set forth in the claims and illustrated in the drawings forming a part of this specification in which like characters of reference indicate corresponding parts in all the views, and in which—

Figure 1 is a face view of the closure in place, a portion of the key, however, being broken away; Fig. 2 is a transverse section on the line 2—2 of Fig. 1; Fig. 3 is a sectional view at right angles to Fig. 2, on the line 3—3 of Fig. 1, the view indicating an intermediate stage in the process of assembly; Fig. 4 is a view similar to Fig. 3, with the locking key in a succeeding stage; Fig. 5 is a similar view of the locking key driven home, making the closure complete; and Fig. 6 is a perspective view of the key detached.

The several parts of the device may be made of any suitable materials, and the relative sizes and proportions of the same may

be varied to a considerable extent without departing from the spirit of the invention hereinafter more fully set forth and specifically claimed.

Referring more particularly to the illustrations, I show at 10 a chamber or receptacle which may be understood to be of metal and of such a nature as to render it impossible for an operation to be made from the inside thereof for the purpose of closing the hole 11 formed therein. In other words, it is to be understood that my hole closure is intended to be applied to the plate or box construction, all of the operation being performed from one side only of such plate. In many cases in practice it is required to close holes of candy boxes, for instance which are all in place and the interiors of which are not accessible for this reason.

The closure includes a substantially flat plate 12, in this case consisting of a substantially circular member incidental, however, to the form of the hole 11. Said plate 12 is made of any form so as to cover the hole at least a little larger in area so as to provide an overlapping margin 12'. As shown in Figs. 1 and 2 especially, the plate 12 is stamped or otherwise formed with a series of projections or tongues shown at 13 and 14. The lugs 13 are struck inwardly adjacent the margin 12' for co-operation with the rim or edge 11' of the hole 11 for limiting the sliding movement of the plate 12 in one direction viz., at right angles to the line joining the lugs 13. The margin 12' of the plate, therefore, at this part is left entire. The tongue 14, however, is formed from the outer edge of the plate or margin 12' and is bent inwardly and projectable beneath the rim of the hole 11, as shown in Figs. 3 and 4, these figures indicating the normal form of the tongue 14 as constructed. The plate 12, therefore, may readily be applied to the hole 11 by extending the hook end of the key 15 through the hole and then giving the plate a slight sliding movement, bringing the free end of the tongue 14 beneath the plane of the rim 11', as shown in Fig. 3. The movement of the key 15 by the operator's fingers from the position of Fig. 3 to that of Fig. 4 slides the plate 12 and its tongue 14 to the position of Fig. 4, with the tongue projecting beneath the rim 11'. During this movement of the key it acts as a lever of the second class, the fulcrum being at the edge of 110

the hole 11 opposite the tongue 14 and with part of the key just above the fulcrum acting to shove the plate as stated above.

Any suitable means may be provided to lock the closure plate 12 in the position just described. I prefer, however, to employ a key 15 of the form illustrated in which there is formed an angularly shaped hook 16 at one end, a substantially flat bar 17, 10 and a bow-shaped tongue 18 at the opposite end. The hook 16 includes an inwardly projecting stem 16' and a point 16'' extending normally at a slight acute angle from the stem and engaging beneath the rim 11' of the box. The stem 16' is so formed to correspond with the thickness of the metal of the box and the plate as to cause a binding effect between the plate and the box when the key 15 is forced from the position shown in Fig. 3 to that in Fig. 4. This binding effect is intensified by the acute angular formation above described and shown in Fig. 6. The key, therefore, 20 will be understood to be made preferably 25 of a comparatively soft metal. By the provision of the substantially flat bar 17 of the key, the clamping or gripping effect of the hook 16 is not relieved when the tongue 18 is flattened out into the form or position 30 shown in Fig. 5. In other words, there is no substantial variation in gripping effect of the hook between the positions shown in Figs. 4 and 5.

The stem and point of the hook 16 may 35 be caused to operate with the plate 12 in any suitable way, but as shown herein, there is provided a seat 19 in the nature of a notch or opening formed in the plate adjacent the margin 12' diametrically opposite the tongue 14. The seat is of a width just a little, if any, greater than the width of the key so that when the devices are in final position there will be practically no opening through the structure. Referring 40 again to Fig. 3, it will be observed that with the parts as there shown it is but a simple operation of the thumb to force the tongue down into contact with the tongue 14 and with the point 18' of the tongue into temporary locking engagement with the rim 11' 45 as well as in contact with the plate tongue, as shown in Fig. 4. It remains, therefore, but for a slight tap to be given to the bow 18 to force the point 18' thereof through between the tongue 14 and the rim 11' completing the interlock, as shown in Fig. 5. This operation of the key forces the tongue 14 inwardly slightly out of normal position, 55 making a close fitting closure. The key 15, therefore, positively prevents movement of the plate 12 in either direction parallel to the axis of the key, and the lugs 13 prevent movement of the plate in either direction at right angles to said axis.

60 So far as the description thus far given

is concerned, the plates and the keys may be made and used separately, but I have found in practice that there is sometimes inconvenience occasioned by danger of loss or misplacement of the keys when they are not permanently connected to the plates. 70 To avoid this objection, therefore, I provide the hook portion of each key with lateral extensions 20 which may be formed by operation of the die in the formation of the key or in any other suitable manner, 75 whereby the key is made wider than the seat 19 on the outside as well as on the inside, whereby the key is prevented from longitudinal movement or displacement through 80 the seat opening. The plate is formed with a pair of fingers 21 which extend outwardly, as shown in dotted lines in Fig. 1, but which may be forced inwardly toward each other, 85 as shown in full lines, retaining the key in the seat 19 and hence making it impossible for the key to be lost from the plate during the ordinary preliminary manipulation of the apparatus. In order to open the hole 11 after being closed by this device, the application of a screw driver or other simple tool under the middle portion of the key 15 is sufficient to withdraw it from its locking position shown in Fig. 5, and then the plate 90 may be removed by simply sliding it in the reverse direction to that described above 95 during the operation of closing the hole.

Having thus described my invention, I declare as new and desire to secure by Letters Patent:—

100

1. The herein described hole closure comprising a plate larger than the hole, said plate being formed with a pair of oppositely arranged inwardly projecting lugs adapted to substantially engage the edge of the rim 105 of the hole to limit the sliding movement of the plate at right angles to the line joining said lugs, the plate also being provided with an inwardly extending tongue, the free end of which is adapted to engage beneath said rim, and a bendable key coöperating with the outer surface of the plate and tongue and engaging within the structure having the hole serving to prevent displacement of the plate. 110

115

2. The herein described closure for a hole, the same comprising a plate larger than the hole, said plate having parts bent inwardly for coöperation with the rim of the hole, and a key spanning the outer surface of the plate 120 and having at one end a hook serving to grip one portion of the plate to the rim of the hole and said key at the other end having a tongue adapted to be forced into interlocking coöperation with the hole rim, securing to the hole rim the portion of the plate opposite said gripped portion. 125

130

3. The herein described hole closure comprising a plate adapted to be applied over said hole, said plate being formed with a 130

plurality of inwardly extending projections coöperating with the hole rim, one of said projections extending beneath the rim, and a key, said key including a hook at one end 5 adapted to engage the inner surface of the hole rim, and a bar adjacent said hook adapted to lie snugly against the outside of the plate, and a tongue at the other end of the key adapted to be forced inwardly between the hole rim and the plate projection 10 extending therebeneath.

4. The herein described hole closure comprising a substantially flat plate larger than the hole to be closed, said plate having 15 formed therein a pair of integral studs projecting inwardly from the margin of the plate in to coöperation with the edge of the hole rim, said plate also having an integral tongue extending inwardly beneath the hole 20 rim, there being formed in the plate opposite the tongue a seat, and a key spanning the outside of the plate and having its ends extending beneath and interlocking with the rim of the hole, one of said ends being extended through said seat and the other end 25 being forced between said plate tongue and the hole rim.

5. In a hole closure, the combination of a plate having integral parts adapted to co-

operate with and limit the extent of movement of the plate upon a hole rim, and a locking key connected permanently with said plate, spanning the outside thereof and having its ends adapted to interlock with the under surface of said rim. 30

6. The herein described closure for a hole through a plate, the same comprising a flat metal plate slightly larger than the hole to be closed, said closure plate being provided with an integral tongue extending inwardly 40 from one side thereof and beneath the rim of the hole to be closed, said closure plate being provided with a notch on the side thereof opposite the tongue, and a key spanning the outer surface of the closure plate, 45 one end of the key projecting through said notch and beneath the adjacent hole rim, and the other end of the key being adapted to be forced downwardly into clenching co-operation with said tongue beneath the adjacent portion of the hole rim. 50

In testimony whereof I have signed my name to this specification in the presence of two subscribing witnesses.
